UNITED STATES PATENT OFFICE.

CALVIN C. FOUTS, OF MIDDLETOWN, OHIO.

SILO-DOOR.

1,141,703.

Specification of Letters Patent.

Patented June 1, 1915.

Application filed August 7, 1914. Serial No. 855,544.

To all whom it may concern:

Be it known that I, CALVIN C. FOUTS, a citizen of the United States, residing at Middletown, Butler county, Ohio, have invented certain new and useful Improvements in Silo-Doors, of which the following is a specification.

In silos of the type and construction to which this invention is particularly applicable there is a vertical shell and a vertical series of doors in the shell, ladder devices being provided at the series of doors to facilitate access to the several doors. The doors should be of simple construction, fairly if not perfectly watertight; opening inwardly; controlled from the outside of the silo; and the interior surface of the door should be, as far as practicable, flush with the interior of the shell to permit of easy slippage of the ensilage.

The present invention, relating to the construction of such silo doors will be readily understood from the following description taken in connection with the accompanying drawing in which:

Figure 1 is a front elevation of my improved silo door with its door-ring, portions appearing in vertical section; and Fig. 2 a section of the same in the plane of line *a* of Fig. 1.

In the drawing:—1, indicates the shell of the silo, which may be of metal or wood, my present invention being, however, designed with metallic silo shells particularly in view, this shell being provided with a door-opening of the size and form thought most expedient, the illustration being founded on a door-opening circular in form; 2, a jamb-ring secured to the shell around the door-opening, on the exterior surface of the shell and projecting outwardly from the outer surface of the shell and having a portion projecting radially inward of the margin of the door-opening at the outer extremity of said outward projection; 3, a groove formed in that portion of the jamb-ring projecting inwardly of the margin of the door-opening, this groove presenting itself inwardly to the body of the silo; 4, a packing, which may be of treated wicking or analogous material disposed in the groove 3 of the jamb-ring; 5, the door, the same being of the size and form to freely enter and fairly fill the door-opening in the shell and having its interior surface substantially flush with the interior sur-

face of the shell; 6, an outwardly projecting flange formed on the periphery of the door and adapted to freely enter the groove in the jamb-ring and seat against the packing in the groove; 7, a double hinge disposed inside the shell and door and connecting these two parts, by double hinge being meant a hinge with two pivots, somewhat similar to the crane-hinge of a burglar-proof safe, so that the door may start its opening motion in a line substantially parallel with the axis of the door, this motion taking place on one pivot of the hinge, while the continued opening motion of the door may take place on the second pivot of the hinge or on both pivots combined; 8, a bar rigidly secured to but at some distance from the outer surface of the door and serving as a ladder-rung, and as means by which the door may be manipulated; 9, levers having their outer ends pivoted to the shell of the silo in a circumferential series around the door-opening, these levers projecting inwardly over the jamb-ring and past the inner periphery thereof, there being as many of these levers as are deemed necessary, the illustration showing four of them; 10, pivots connecting the levers with the shell; and 11, bolts projecting outwardly from the door and passing through the inner ends of the levers, which levers are provided with slotted openings to permit the presence of the bolts and to permit of the levers being swung outwardly beyond the periphery of the door-opening in the jamb-ring when the door is to be opened.

Considering the door in its closed position, as indicated, it is held firmly closed with the outer edge of its flange 6 against the packing 4 by the leverlike action of levers 9, and with its inner surface as flush and continuous with the inner surface of the shell as is consistent with the presence of hinges at the inner surface of the door. In this condition of the door the door-opening is tightly sealed and ladder-rung 8 may act in conjunction with ladder-rungs on similar doors arranged in a vertical series and in conjunction with ladder-rungs on the silo shell between the doors of the vertical series. When the door is to be opened then the nuts on bolts 11 are slackened sufficiently to permit levers 9 to be swung upon their pivots to such position that they will not project inside the door-opening. The door may then be opened inwardly, the ladder-rung

acting as a door-handle, and the first opening motion of the door may be almost directly inward, by reason of the double hinge, the latter opening motion of the door being by 5 the usual hinging action. When the door is completely opened and swung back against the in wall of the shell then the ladder-rung takes position inside the silo.

I claim:—

- 10 1. A silo door construction comprising, a jamb-ring secured at the door-opening in the silo shell and projecting outwardly from the outer surface of the shell and having its outermost portion projecting inwardly 15 beyond the margin of the door-opening, packing held by such inwardly projecting portion of the door-jamb, a door seated in the door-opening in the shell and having its interior surface substantially flush with the 20 interior surface of the shell, a flange projecting away from the outer surface of the door and adapted to make contact with said packing, a hinge disposed within the shell and 25 uniting the door to the shell, and fastening devices coöperating with the exterior of the shell and door and serving to draw the door outwardly, combined substantially as set forth.
2. A silo door construction comprising, a 30 jamb-ring secured to the outer surface of the silo shell and projecting outwardly therefrom around the door-opening and having

a portion projecting radially inward of the door-opening, a packing carried by said radially inwardly projecting portion of the 35 jamb-ring, a hinged door mounted for opening inwardly and adapted to seat against such packing, levers having their heels secured to the shell outside the jamb-ring and engaging over the outer face of the 40 jamb-ring and projecting radially inward thereof, and bolts carried by the outer face of the door and adapted to engage the inner ends of said levers and draw the levers against the outward projection of the jamb-ring and draw the door against said packing, combined substantially as set forth. 45

3. A silo door-construction comprising, a jamb-ring secured to the silo shell and projecting outwardly therefrom, a door 50 adapted to open inwardly and to close outwardly against the jamb-ring, pivots carried by the shell around said jamb-ring, bolts carried by the door in correspondence with the position of said pivots, and levers resting on the outer projection of the jamb-ring and having their outer ends mounted on said pivots and their inner ends engaged by said bolts, combined substantially as set forth. 55
